FRANK E. WILLIAMS AND OLIVER S. BARNUM, OF ALHAMBRA, CALIFORNIA.

NECKTIE-CLASP.

1,399,233.

Specification of Letters Patent.

Patented Dec. 6, 1921.

Application filed January 9, 1920. Serial No. 350,338.

To all whom it may concern:

Be it known that we, FRANK E. WILLIAMS and OLIVER S. BARNUM, citizens of the United States, and residents of the city of Alhambra, county of Los Angeles, and State of California, have invented jointly new and useful Improvements in Necktie-Clasps, of which the following is a specification.

The objects of this invention are to provide a clasp as for a gentleman's neck-tie that will not allow the material placed therein to slip, that locks positively and automatically, can be released only by manipulation of the finger, and to construct the same in an attractive and cheap manner.

We attain these objects by the mechanism illustrated in the accompanying drawings, in which—

Figure 1 is a side view of the complete invention with the clasping element released to allow insertion of the neck-tie or other material.

Fig. 2 is a similar view of the complete invention with the clasping element in position to compress and hold the neck-tie, and securely locked.

Fig. 3 is a view of the mechanism from above, the front or face of the clasp being cut away.

The invention embraces a U formed body 1, designated on the drawings as divided into face 1^a, base 1^b and curve 1^c, provided with longitudinal wings 2 on either side of base 1^b; perforations in said wings 3 to serve as journals for axle 4; and a longitudinal, irregular triangular opening 5 in base 1^b between said wings, terminating in notch 6 at its apex.

The clasping element is a coil spring 7, rotating upon axle 4, one turn or end of said coil being elongated to form a loop or tongue 8 the extremity of which may be made to impinge upon the inner surface of face 1^a, another turn or end being elongated to form lever arm 9 which serves to rotate coil 7 and bring the extremity of tongue 8 in contact with the inner surface of face 1^a.

Upon pressing upward on lever arm 9, and so soon as it begins to enter opening 5, said lever arm comes in contact with edge 10 of said opening at a very acute angle, thus causing a progressive lateral pressure on said lever arm as it advances into opening 5 until

it reaches notch 6 when it automatically springs into said notch. At the same time 55 coil 7 is caused to rotate and the extremity of tongue 8 is made to impinge upon the inner surface of face 1^a. To more effectively prevent slipping of material held between tongue 8 and face 1^a a depression 11 is provided in face 1^a at the point of impingement. 60

When the clasping element is so rotated and locked, as shown in Fig. 2, to release lever arm 9 from notch 6 it is only necessary to exert slight pressure with the thumb nail 65 on the returning part of lever arm 9 which projects below base 1^b, whereupon, by resiliency of the tense coil 7, it will spring into the position of release shown in Fig. 1.

It is essential that body 1 shall be approximately rigid, varying thickness of material inserted between tongue 8 and face 1^a being compensated for by the resiliency of coil 7. To secure the desired rigidity curve 1^c is reinforced by ribbing, winged edges, or in 75 any other manner thought desirable.

In a modification of the construction above set forth it will be apparent that should the sides of longitudinal opening 5 be parallel as in Fig. 3, then and in that case the automatic springing of arm 9 into notch 6 for the purpose of locking said arm may be accomplished by bending arm 9 toward the notched side of opening 5 at an angle slightly less than 90 degrees from the axis of coil 7, thus 80 preserving the relative angle of contact between said arm and said notched side as said arm 9 advances into said opening. 85

Having thus described our invention and its manner of operation, we claim as new and desire to obtain Letters Patent of the United States upon—

1. In a clasp of the character disclosed, a U-shaped body; a clasping element comprising a revolute, yielding clasping member 95 pivotally supported in one arm of said body; and means for retaining said yielding member in clasping relation with the inner side of the other arm of said U-shaped body; said clasping member comprising a material engaging tongue and a finger lever in yielding relation thereto by means of an interposed coil spring.

2. In a clasp of the character disclosed, a U-shaped body; a clasping element comprising 105 a revolute coil spring formed of a

length of metallic wire pivotally supported in one arm of said U-shaped body; one turn of said coil spring being elongated to provide a clasping tongue to co-act with the inner surface of the second arm of said U-shaped body in clasping action; another turn of said coil spring being elongated to provide a finger-lever in yielding relation to said tongue and whereby said tongue may be urged into clasping relation with said inner surface of said second arm of said U-shaped body, to clasp the material lying between said arms.

3. A clasp of the character disclosed formed of a strip of suitable material bent upon itself to form a U-shaped body whose two arms provide a face and a base adapted to receive between them the material to be clasped; a clasping element comprising a revoluble coil spring formed of a length of metallic wire pivotally supported in the base arm of said U-shaped body; one turn of said coil spring being elongated to provide a clasping tongue to co-act with the inner surface of the face arm of said U-shaped body in clasping action; another turn of said coil spring being elongated to provide a finger-lever in yielding relation to said tongue and whereby said tongue may be urged into clasping action upon the material lying between said face and base arms; there being means for releasably holding said finger-lever in repressed position.

4. A clasp of the character disclosed formed of a strip of suitable material bent upon itself to form a U-shaped body whose two arms provide a face and a base adapted to receive between them the material to be clasped; said base being provided with longitudinal wings on either side thereof; an axle-pin passed through perforations in said wings and ranging transversely thereto; said base being further provided with an irregular longitudinal opening between said wings and terminating in a transverse notch at its extremity nearest the U-bend of said body; a coil spring formed of a length of metallic wire rotating on said axle-pin within said opening, and formed to provide a tongue to co-act with the inner surface of said face in clasping action, and a finger-lever in yielding relation to said tongue for rotating said coil and positioning said tongue; there being means on said base for holding said finger-lever in position with said tongue in repressed clasping action.

5. A clasp of the character disclosed formed of a strip of suitable material bent upon itself to form a U-shaped body whose two arms provide a face and a base adapted to receive between them the material to be clasped; said base being provided with longitudinal wings on either side thereof; an axle-pin passed through perforations in said wings and ranging transversely thereto;

said base being further provided with an irregular longitudinal opening between said wings and terminating in a transverse notch at its extremity nearest the U-bend of said body; a coil spring formed of a length of metallic wire rotating on said axle-pin within said opening, and formed to provide a tongue to co-act with the inner surface of said face in clasping action, and a finger-lever in yielding relation to said tongue for rotating said coil and positioning said tongue; said finger-lever being bent upon itself at suitable length to provide a loop adapted to readily spring sidewise into said notch.

6. A clasp of the character disclosed formed of a strip of suitable material bent upon itself to form a U-shaped body whose two arms provide a face and a base adapted to receive between them the material to be clasped; said base being provided with longitudinal wings on either side thereof; an axle-pin passed through perforations in said wings and ranging transversely thereto; said base being further provided with an irregular longitudinal opening between said wings and terminating in a transverse notch at its extremity nearest the U-bend of said body; a coil spring formed of a length of metallic wire rotating on said axle-pin within said opening and formed to provide a tongue to co-act with the inner surface of said face in clasping action, and a finger-lever in yielding relation to said tongue for rotating said coil and positioning said tongue; said finger-lever being bent upon itself at suitable length to provide a loop adapted to readily spring sidewise into said notch; said inner surface of said face being provided with a depression at the point of impingement of said tongue.

7. A clasp of the character disclosed formed of a strip of suitable material bent upon itself to form a U-shaped body whose two arms provide a face and a base adapted to receive between them the material to be clasped; said base being provided with longitudinal wings on either side thereof; an axle-pin passed through perforations in said wings and ranging transversely thereto; said base being further provided with an irregular longitudinal opening between said wings and terminating in a transverse notch at its extremity nearest the U-bend of said body; a coil spring formed of a length of metallic wire rotating on said axle-pin within said opening, and formed to provide a tongue to co-act with the inner surface of said face in clasping action, and a finger-lever in yielding relation to said tongue for rotating said coil and positioning said tongue; said finger-lever being bent upon itself at suitable length to provide a loop adapted to readily spring sidewise into said notch; said inner surface of said face being provided with a 130

depression at the point of impingement of said tongue; said base being further provided with a longitudinal depression on its inner surface at the edge of said notch and
5 adapted to receive said finger-lever when lying in said notch.

In testimony whereof, we have signed our

respective names to this specification in the presence of two subscribing witnesses.
